(57) **CLAIM**

The ornamental design for an electrosurgical generator as shown and described.

DESCRIPTION

FIG. 1 is a front, top, right perspective view of an electrosurgical generator according to our new design;

FIG. 2 is rear, top, right perspective view of the electrosurgical generator shown in FIG. 1;

FIG. 3 is front, top, left perspective view of the electrosurgical generator shown in FIG. 1;

FIG. 4 is rear, top, left perspective view of the electrosurgical generator shown in FIG. 1;

FIG. 5 is a front elevational view of the electrosurgical generator shown in FIG. 1;

FIG. 6 is a rear elevational view of the electrosurgical generator shown in FIG. 1;

FIG. 7 is a right side elevational view of the electrosurgical generator shown in FIG. 1;

FIG. 8 is a left side elevational view of the electrosurgical generator shown in FIG. 1;

FIG. 9 is a top plan view of the electrosurgical generator shown in FIG. 1; and,

FIG. 10 is a bottom plan view of the electrosurgical generator shown in FIG. 1.

The evenly spaced dashed lines in the drawings depict portions of the electrosurgical generator that form no part of the claimed design. The dot-dash broken lines depict the bounds of the claimed design and form no part thereof.

1 Claim, 8 Drawing Sheets
